PARCEL BAG

Robert M. Lackey, Cohoes, N. Y.

Application May 9, 1934, Serial No. 724,639

10 Claims. (CL. 229—68)

Among the principal objects which the present invention has in view are: To provide means for preventing the sides of the bag from pulling apart when loaded to capacity; to provide means for maintaining the service or working position of the cover flap with which the bag is provided, and to simplify the construction and facilitate the manufacture thereof.

Drawings:

10 Figure 1 is an out-spread view of a blank with which the herein described parcel carrying bag is constructed.

15 Figure 2 is an enlarged detail view of a fragment of the handle-forming portion of the parcel-carrying bag, the members being disposed in position to receive the contents which they are to carry.

20 Figure 3 is a similar view showing the position of the members assumed when the cover flap has been moved to closure position.

Figure 4 is a similar view showing the further development of the closure of the bag, the handle members having been aligned in position to be locked.

25 Figure 5 is a sectional view, the section being taken on the line 5—5 in Figure 4.

Figure 6 is a similar view showing the opposite side of the bag to emphasize the relation of the handle finger opening and the locking member of the handle.

30 Figure 7 is a view showing the service position of the completely folded bag.

Figure 8 is a sectional view, the section being taken on the line 8—8 in Figure 7.

35 Description:

It is the intention and purpose of the present construction to augment the carrying capacity of the bag, and to strengthen the handle members to the end that the bag may be employed for carrying loads which heretofore would have been thought excessive.

40 By reference to Figure 1 of the drawings it will be seen that the patches 12 and 13 are complementary, or in other words, that the outline forming the handle member 14 of the patch 13 corresponds with the exposed outline of the cross bar 15 of the closure flap 16. This construction accommodates the method of manufacture of the bag when a continuous strip of paper is fed to a bag making machine, a series of reinforcing patches having the combined outline of the patches 12 and 14 are adhered to the continuous bag body as the same is carried into and through the machine.

45 The patches 12 and 13 are preferably con-

structed from relatively heavier and stronger material than the body of the bag, the purpose being to render the structure more capable of performing the service desired and to render the handle members more rigid.

5 In the source of manufacture, the blank shown in Figure 1 is folded on the score line indicated by the numeral 17 so that the handle member 14 will overlie the handle member 18 in service. The handle member 14 and parts associated therewith are preferably disposed for delivery to the trade in the position shown in Figure 2 of the drawings wherein the said handle member 14 is folded back upon the body of the bag. In this position it will be observed the bag may be 15 quickly and easily opened by lifting the body portion to receive the contents to be carried. During this operation of loading, the closure flap with its cross-bar 15 and handle member 18, it will be understood, remains in the open or out 20 of service position.

The contents having been disposed within the bag, the closure flap 16 and cross-bar 15 are folded over the opening of the bag, the cross-bar 15 overlying the body of the patch 12 at the lower 25 side of the finger opening A, as seen best in Figure 3 of the drawings. The handle member 13 is then swung up and over the said cross-bar locking the same and the closure flap 16 in service position. When the handle members and closure 30 flap are in this position, as seen best in Figure 4 of the drawings, the locking member 19 with which the handle member 14 is provided, can be forced through the finger openings A and B, as seen best shown in Figures 7 and 8, of the 35 drawings.

It will now be noted that in partially severing the locking member 19 from the body of the handle member 14, the member 19 is provided with extensions 20. These increase the lateral 40 dimension of the locking member 19 beyond the length of the finger opening A to permit the extensions 20 to flex through the said finger openings. The material forming the extensions 20 is cut back as indicated by the numeral 21 so 45 that the distance between the cuttings is less than the length of the finger opening 10. The result of this construction is that when the locking member 19 is forced through the finger opening as above described the extensions 21 snap 50 through the openings and overlie the handle member 18 as shown best in Figures 4, 6 and 7 of the drawings.

It will now be seen that after the member 19 has been thus disposed, any effort to open the 55

bag will cause the extensions 20 to ride down on the outer side of the handle member 18 to prevent the member 19 being accidentally pulled through the finger opening A.

5 It is obvious that when it is desired to re-open the bag, this can be easily done by pressing back the extremities of the member 19 so that the extensions 20 will pass through the finger opening. The material from which the member 19 and the 10 extensions 20 thereof is constructed has sufficient resiliency to re-establish the locked position when the bag is again closed in the manner above described.

15 The arrangement above described is provided to permit the fold crease of the flap 16, to coincide with the finger opening A, as seen best in Figures 2 and 3 of the drawings.

As shown in Figure 3, when the flap 16 is brought down, the barred section 15 of said flap 20 rests below the finger opening A, approximately in line with the lower edge of said opening.

When now the handle member 14 is turned upward to overlie the section 15, (see Figure 4), the finger opening in said handle member 14 registers 25 with the finger opening in handle member 18. Also, it should be noted that locking member 19 registers with the finger openings, and can now be thrust therethrough, the extensions 20, yielding to permit said locking member to pass.

30 It is obvious that as long as the member 19 remains in the position shown, it is impossible to open the bag accidentally, unless perchance, the locking member 19 is retracted backward through the said openings. To prevent this the extensions 35 20 override the sides of the handle member 18 to prevent the locking member 19 to thus retract.

When shaping the handle member 18, it will be noted that the edge of the handle member and of the flap 16 at the folding line of the flap is 40 curved, the purpose of the construction being to counteract any tendency to tear away from the body, and to facilitate folding the flap on the crease of same.

The parcel bags are delivered when the closure 45 flap 16, and handle member 14, are in position as shown in Figure 2 of the drawings. In this position of said parts, the parcel bags are packed ready for use by the person employed as "wrappers" or to place the goods to be carried in said bags. By so arranging the parts, it will be noted 50 that the operations of filling are simplified and the locking operation is indicated as one of the steps in closing the bags.

I claim:

55 1. A bag as characterized having carrying handle members therefor and a closure flap thereof, said handle members and closure flap being reinforced by relatively stronger material adhered to the part from which the handle members are constructed to extend beyond the lateral limits of said handle members, the central portion of said flap being complementary to both handle members, one of said handle members having been severed in part from said flap, and 60 means for locking said handle members in service position to prevent the accidental release of said flap.

2. A parcel bag having a front portion and a back portion integrally united and folded one 70 upon the other with the edges intersecting the line of folding juxtaposed and secured together to form a carrying receptacle having a top opening, said portions being each provided with handle-forming members, said members having each a finger perforation formed therein said

perforations adapted to register each with the other to jointly form a carrying handle for said bag, the perforation in one of said members being longer than the other perforation and formed by a partially severed center portion, said portion being adapted for extension through the other perforation to lock the said members in service relation, a closure flap for said bag integrally formed with one of said body portions to be folded at the bag opening edge of the other body portion, said flap having a cross-bar formed at the mid-length thereof to register with and extend below the finger opening of the handle member with which it is structurally associated to rest in service between said handle members.

15 3. A parcel bag having a front portion and a back portion integrally united and folded one upon the other with the edges intersecting the line of folding juxtaposed and secured together to form a carrying receptacle having a top opening, said portions being each provided with handle-forming members, said members having each a finger perforation formed therein, said perforations adapted to register each with the other to jointly form a carrying handle for said bag, the perforation in one of said members being longer than the other perforation and formed by a partially severed center portion, said portion being adapted for extension through the other perforation to lock the said members in service relation, a closure flap for said bag integrally formed with one of said body portions to be folded at the bag opening edge of the other body portion, said flap having a cross-bar formed at the mid-length thereof to register with and extend below the finger opening of the handle member with which it is structurally associated to rest in service between said handle members, said handle members and cross-bar being structurally reinforced by laminations of relatively stronger material 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 through which extended to prevent the accidental withdrawal thereof from said finger openings.

6. A parcel bag having a front portion and a back portion integrally united and foldable one upon the other, means for securing said portions in service relation, said means embodying a plurality of handle members having each a finger opening therein, said openings substantially conforming each with the other, and a closure flap for said bag on one of said portions, the folding crease whereof alines approximately with the upper edge of the finger opening of the handle member of said portion having said flap.

7. A parcel bag having a front portion and a back portion integrally united and foldable one upon the other, means for securing said portions in service relation, said means embodying a plurality of handle members having each a finger opening therein, said openings substantially conforming each with the other, and a closure flap for said bag, the folding crease whereof alines approximately with the upper edge of the finger opening of the handle member of said front portion, an outer edge of the handle intervening between and being curved to lead into the folding crease of said flap.

8. A parcel bag having front and back portions each having carrying means providing substantially registering finger openings, one of said carrying means providing a locking member hinged thereto and capable of insertion through the other opening, said locking member providing locking means in the plane of the locking member

and projecting past the line of hinging on the opposite side thereof from the body of the locking member.

9. A parcel bag having front and back portions each having carrying means providing substantially registering finger openings, one of said carrying means providing a locking member hinged thereto and capable of insertion through the other opening, said locking member providing locking means in the plane of the locking member 10 and projecting past the line of hinging on the opposite side thereof from the body of the locking member, the distance in the direction of the line of hinging between the outermost edge of one of the locking means to the outermost edge of 15 the other locking means being greater than the distance between ends of the finger opening through which said locking means is inserted and juxtaposed in service relation next to the line of hinging of the locking member. 20

10. A parcel bag having front and back portions with a receiving opening therebetween and each having carrying means providing substantially registering finger openings when in service relation, one of the portions with one of said carrying means having a continuation adapted to extend beyond the other said portion and carrying means, and the other carrying means adapted to be folded downwardly to rest in flattened condition against the other of said portions whereby the bag is out 25 of service condition and delivered to the trade 30 in open position and ready for use.

ROBERT M. LACKEY.
